PROTECTIVE COVER FOR AN ELECTRONIC DATA TERMINAL

Joseph B. Ray, Jr., Atlanta, Ga.
(4405 Mall Blvd., Suite 501, Union City, Ga. 30291)

Filed June 10, 1974, Ser. No. 477,820

Term of patent 7 years

Int. Cl. D3—02

U.S. Cl. D87—1 R

FIG.1

FIG.2

FIG.3

FIG.4

FIG. 1 is a front perspective view of a protective cover for an electronic data terminal showing my new design;

FIG. 2 is a side elevational view thereof;

FIG. 3 is a top plan view; and

FIG. 4 is a rear elevational view.

I claim:

The ornamental design for a protective cover for an electronic data terminal, as shown.
